The ornamental design for a lamp base with clock, as shown and described.

DESCRIPTION

FIG. 1 is a top, left side, front perspective view of the lamp base with clock having my new design;
FIG. 2 is a top plan view thereof;
FIG. 3 is a front elevational view thereof;
FIG. 4 is a right side elevational view thereof, the left side being a mirror image hereof;
FIG. 5 is a back elevational view thereof; and,
FIG. 6 is a bottom plan view thereof.

The columns of FIGS. 1 and 3-5 are shown broken-away to indicate indeterminate length; and the broken-line showing of FIG. 1 is for environmental purposes only and forms no part of the claimed design.
